UNITED STATES PATENT OFFICE.

PETER C. REILLY, OF INDIANAPOLIS, INDIANA.

STILL.

1,310,874.

Specification of Letters Patent. Patented July 22, 1919.

Application filed March 28, 1914. Serial No. 827,967.

To all whom it may concern:

Be it known that I, PETER C. REILLY, a citizen of the United States, residing at Indianapolis, in the county of Marion and State of Indiana, have invented certain new and useful Improvements in Stills, of which the following is a specification.

My present invention pertains to an improved still designed more particularly for the distillation of coal tar, though susceptible of use for the distillation of other materials such, for instance, as petroleum.

The still in its simplest form is disclosed in the annexed drawings, wherein:

Figure 1 is a longitudinal vertical sectional elevation of the still and its setting; and

Fig. 2 a transverse sectional view thereof, on the line 2—2 of Fig. 1.

The main object of the invention is to provide a still in which coal-tar may be distilled so as to drive off all the volatile portions of the charge, producing certain substances or products not heretofore commercially known, and likewise forming a coke, sponge-like in appearance which, along with the products (distillates), has a commercial value.

In the drawings, I have disclosed a simple form of still and housing or mounting, wherein 1 indicates the still proper, shown in the form of a cylindrical chamber and provided with a manhole 2 in the upper portion thereof, and a manhole 3 opening into the lower portion of the still through one end or head thereof. A pipe 4 extends from the upper portion of the still and carries off the products which are formed, owing to the action of the heat, as is well understood. The fire-chamber is indicated by 5, and as will be noted is preferably located adjacent the front wall 6 of the housing and over said fire chamber I provide a fire arch 7, the products of combustion passing outwardly through a flue or opening 8, formed beneath said arch and the inner wall 9 of the fire chamber. The outlet for the products of combustion is indicated by 10, and, as will be noted, it is located in the rear wall 50 of the housing, at the lower portion thereof, said opening discharging into a lateral flue 11, which flue extends to a stack, which is not shown. In practice, a battery of stills is employed, the housings all being alike 55 and the lateral flue 11 serving all of the stills. A fire wall 12 guards the outlet 10,

said wall extending well upwardly toward the lower portion of the still so that the products of combustion cannot pass directly from the opening 8 to the outlet 10. 60 Naturally the products of combustion being the hottest as they emanate from the opening 8, will rise and come into contact with the still. As noted, the still is spaced away from the wall of the housing throughout, 65 and is supported by brackets 13 riveted to the sides of the still and resting in the brickwork or the walls of the still housing. Thus it will be seen that except for the relatively small area of contact of the manholes 70 2 and 3, the pipe 4, and the brackets 13, the still is suspended in space in the upper portion of the housing and is subjected on all sides to the products of combustion passing from the furnace. 75

From an examination of the drawings, it will be noted that there are no pipes or flues extending into or through the still, and the same may be said to have a substantially unobstructed interior. Where pipes, flues 80 or the like are carried into and through the still, there is a tendency for the carbon to deposit thereon, and to thereby impede the operation of the still. Once the carbon forms and remains upon the pipes or flues 85 it is quite difficult to remove it, and said members will burn out unless it be removed.

With a still thus constructed, housed and mounted I have been able to distill coal tar upon a large scale commercially, treating a 90 charge of anywhere from 4500 to 5000 gallons in a still approximately seven feet in diameter by sixteen feet six inches long, complete distillation being effected in from eighteen to thirty six hours, according to the 95 nature of the coal tar being distilled. All the volatile portions of the charge will, within the time above specified (when the temperature is run up to 1000° F.) be driven off and the residue in the still takes 100 the form of a dry coke, sponge-like in character, which is easily removed from the still.

During the first portion of the distillation of the coal tar (assuming that coal tar and 105 not coal tar pitch is placed in the still), the operation is as usual; that is to say, the water followed by the light oils (phenol group) first passes over. The heavier oils then pass over, such oils containing naphthalene and 110 the beginning of the anthracene. These are followed by the anthracene. Such products,

of course, are well known and commercially derived from coal tar. From this point on, however, my method and operation are different from those heretofore known. Ordinarily, where the heat is applied merely to the under portion of the still, such portion acquires at first a semi-solid deposit and finally a solid deposit, practically dry, and to a large degree impervious to heat, so that the liquid mass lying above such coating or deposit cannot be reached by the heat applied to the bottom of the still. The residue or matter lying above such layer is still undistilled and contains a large quantity of volatile matter of a high specific gravity, which I have 10 discovered contains valuable material, particularly for use as preserving compounds for the treatment of wood, with the view of waterproofing the same.

With a still such as herein set forth I am 20 enabled to produce a final or ultimate distillation of all the volatile portions, leaving a perfectly dry and easily removable coke. This is due to the fact that the heat is applied to the entire still surface, and when an oil is once separated it passes out of the still at once and there is no condensation of the material in the upper portion of the still and a consequent dropping back into the mass 25 below, as takes place in the commercial still of today.

The use of a still as herein set forth, not only produces the materials above specified, which have a high commercial value, but it is 30 also advantageous in the first distillation of coal tar to produce the ordinary products therefrom, in that the heat is applied to the entire still, and the distillation is effected with rapidity and economy.

Having thus described my invention, what I claim is:

1. In an apparatus for obtaining the products of distillation of hydrocarbons, the combination of a metallic still adapted to contain the material to be treated, said still having a free outlet extending directly from the upper part thereof; a furnace for applying heat thereto; and a housing for the still spaced away from and entirely surrounding the same, the arrangement being such that the products of combustion from the furnace may have free access to all portions of the still and the still thereby subjected to a substantially even temperature over its entire surface.

2. In an apparatus for obtaining the products of distillation of hydrocarbons including coal tar and coal tar pitch, the combination of a metallic still having a substantially 60 unobstructed interior and a free outlet extending directly from the upper portion thereof; a furnace for applying heat thereto; a housing for the still spaced away from and entirely surrounding the same whereby 65 the products of combustion from the furnace

may have free access to all portions of the still; and means for directing the products of combustion to and around the still to effect a substantially even heating thereof over its entire surface whereby coke will be 70 produced upon complete distillation of coal tar or coal tar pitch.

3. In an apparatus for distilling, the combination of a metallic still having a substantially unobstructed interior; a furnace 75 located below the same adjacent one end thereof; a housing for the still located above the furnace and entirely surrounding the still and spaced away therefrom whereby the products of combustion emanating from 80 the furnace may have free access to the entire exterior surface of the still; a manhole for charging the still; a manhole affording access to the lower portion of the still, whereby the ultimate residue of distillation 85 may be removed therefrom; a plurality of brackets extending from the still into the side walls of the housing; and a pipe for conveying the distillates from the still.

4. In an apparatus wherein a complete 90 distillation of hydrocarbons such as coal tar, coal tar pitch and the like may be effected, the combination of a metallic still adapted to contain the material to be treated, the walls of the still being of substantially 95 the same thickness throughout, said still having a free outlet extending directly from the upper part thereof; a furnace for applying heat thereto; and a housing for the still spaced away from and entirely surrounding the same, the arrangement being such that the products of combustion from the furnace may have free access to all portions of the still and the still and the contents thereof will be subjected to an even 100 temperature throughout.

5. An apparatus wherein coal tar and coal tar pitch may be completely distilled to the point of production of a dry coke, which comprises, in combination, a metallic still 110 adapted to contain the material to be treated, said still having a free outlet extending directly from the upper part thereof; a housing for the still entirely surrounding the same, said housing being spaced away from 115 the still so that approximately the entire surface is exposed; and a furnace, the parts being so proportioned and arranged that the still will be subjected to an approximately even temperature over its entire surface.

6. An apparatus wherein coal tar and coal tar pitch may be completely distilled to the point of production of dry coke, which comprises, in combination, a metallic still having a substantially unobstructed interior 125 and adapted to contain the material to be treated, said still having a free outlet extending from the upper portion thereof; a housing for the still entirely surrounding the same, said housing being spaced away 130

from the still so that approximately the entire still surface is exposed; and a furnace, the parts being so proportioned and arranged that the still will be subjected to an approximately even temperature over its entire surface.

7. In an apparatus for obtaining the products of distillation of hydrocarbons, the combination of a metallic still adapted to 10 contain the material to be treated, said still having a free outlet; a furnace for applying heat thereto; and a housing for the still spaced away from and entirely surrounding the same, the arrangement being such 15 that the products of combustion from the furnace may have free access to all portions of the still and the still thereby subjected to a substantially even temperature over its entire surface.
- 20 8. In an apparatus for obtaining the products of distillation of hydrocarbons, the combination of a metallic still adapted to contain the materials to be treated, said still having a free outlet and a substantially un- 25 obstructed interior; a furnace for applying heat thereto; and a housing for the still, spaced away from and entirely surrounding

the same, the arrangement being such that the products of combustion from the furnace may have free access to all portions of the 30 still and the still thereby subjected to a substantially even temperature over its entire surface.

9. In an apparatus for obtaining the products of distillation of hydrocarbons, the 35 combination of a metallic still adapted to contain the material to be treated, said still having a free outlet, the walls of the still being of a substantially uniform thickness; a furnace for applying heat thereto; and a 40 housing for the still spaced away from and entirely surrounding the same, the arrangement being such that the products of combustion from the furnace may have free access to all portions of the still and the 45 still thereby subjected to a substantially even temperature over its entire surface.

In testimony whereof I have signed my name to this specification in the presence of two subscribing witnesses.

PETER C. REILLY.
